UNITED STATES PATENT OFFICE.

HENRY A. WISE WOOD, OF NEW YORK, N. Y., ASSIGNOR, BY MESNE ASSIGNMENTS, TO
WOOD NEWSPAPER MACHINERY CORPORATION, OF NEW YORK, N. Y., A CORPORA-
TION OF VIRGINIA.

METHOD OF MAKING PRINTERS' ROLLERS.

1,208,879.

Specification of Letters Patent.

Patented Dec. 19, 1916.

Application filed May 4, 1914. Serial No. 836,182.

To all whom it may concern:

Be it known that I, HENRY A. WISE Wood, a citizen of the United States, residing at New York, in the county of New York and State of New York, have invented a new and useful Method of Making Printers' Rollers, of which the following is a specification.

This invention relates to printers' rollers made of roller composition, that is glue and glycerin.

The principal object of the invention is to provide a roller of this character which can be used for inking the type or cuts and which also will be capable of standing the high speeds at which presses are run at the present day; and especially to provide a construction by which the roller cannot burst when overheated and yet will have a smooth surface of the usual kind so that it can be used for the purpose of inking the type or cuts.

Reference is to be had to the accompanying drawings in which—

Figure 1 is an end view of a set of inking rolls to which this invention can be applied; Fig. 2 is a transverse sectional view of a roller constructed in accordance with this invention; and Fig. 3 is a longitudinal central sectional view of the same.

In Fig. 1 is shown a part of an inking apparatus involving means for applying ink to a plate cylinder 10. For this purpose is shown an ink distributing cylinder 11 and a soft composition roller 12 contacting with it. Two form rollers 13 are shown contacting with the ink distributing cylinder and also with the plate cylinder 10. In this case also an intermediate roll 14 is shown but it does not constitute part of this invention. A roller made according to this invention is provided with a surface suitable for use as a form, or type inking, roll 13 and it can be used simply as an ink distributing roller 12. These rollers 12 and 13 have usually been made of roller composition, that is glue and glycerin, the proportions being varied to suit the temperature at the time when they are used. As is well known such rollers must be pliable, resilient and have a face that is sufficiently tacky or sticky to cause the ink to adhere to it freely. This type of printers' roller, however, I find to be useless at the high speeds at which certain types of these presses are now run. This is due to the internal friction caused by the rapid contact

of the surface of the roller with the inking cylinders and type. This sets up a heat which is sufficiently great to melt the glue. One way of attempting to overcome this difficulty has been to change the chemical content of the rollers and another has been to place a canvas tube on the outside of the roller to hold the composition which fits snugly therein. This tube or jacket although constituting a part of the roller itself forms a skin which, when the material of the roller melts, will prevent the composition from flying off and smearing the parts of the machine with melted glue and glycerin and it obviously prevents the bursting of the roll as it is called. The woven fabric, however, constitutes a comparatively rough surface and prevents the use of this sort of a roller in the position indicated by the rollers 13 in Fig. 1 although it is suitable for use as the roller 12. In other words it is only an ink-distributing roller and not a form or type inking roller. So far as I am aware the latter has always been made of glue and glycerin composition in this type of press without any attempt being made to prevent bursting except by varying the composition.

In order to provide a form of inking roller 13 which will not burst and will have a smooth surface suitable for applying the ink directly to the type or plates I proceed in the following manner: I use a composition such as has been found practical for this purpose and vary it as usual according to the temperature at which it is to be used. In addition to this I provide a tube 15 of flexible fabric preferably canvas of a diameter slightly less than the diameter of the roller to be made. I place this tube in the mold centering it therein so that it does not touch the cylindrical surface of the mold at any point and the composition is cast in any of the ordinary ways. One way of proceeding is to first cast a core with this canvas tube on the outside, this core being slightly smaller than the diameter of the final mold, then center this whole core with the tube on its outside in the final mold. Then a surface layer is cast by forcing composition into the mold outside the tube. This composition is homogeneous with the composition inside the tube and fills the space between the canvas tube and the walls of the mold and is united with the body of

composition inside. When dry the completed roller is withdrawn and used in the usual manner.

The result in any case is a roller suitable for use as a form roller or as an ink distributing roller which is composed of a homogeneous body of composition but has embedded therein the tube of canvas concentric with the outside surface of the roller and located near the surface. In this way all the strength secured by the ordinary canvas jacket is provided and yet the surface is left in exactly the same condition as that of the ordinary composition form roller and it is capable of use for that purpose.

This construction does not detract in any way from the usefulness of the roller as an ink distributing roller, and in fact when this invention is used both these kinds of rollers can be formed in the same way, thus eliminating the necessity of having two kinds of rollers and two ways of making them.

A roller constructed in accordance with this invention cannot burst when overheated and is therefore capable of being operated at all speeds. Moreover, it prevents the composition flying off the roller when heated and smearing the parts of the machine with melted glue and glycerin. Thus much time and labor usually required to

clean up and start again after such accidents are saved.

Although I have illustrated my invention as applied to a particular type of inking mechanism and shown only a single specific embodiment of the invention, I am aware of the fact that the invention is capable of general use in this art and that the specific form shown can be varied within reasonable limits without departing from the scope of the invention as expressed in the claims. Therefore, I do not wish to be limited in these respects, but

What I do claim is:—

A method of making a printer's roller which consists in centering a tube of flexible material in a cylindrical mold of larger diameter than the tube, keeping the tube out of contact with the cylindrical inner surface of the mold, and molding the roller composition in said mold inside the tube and between the tube and mold to cover and surround said tube.

In testimony whereof I have hereunto set my hand, in the presence of two subscribing witnesses.

HENRY A. WISE WOOD
